AIR-VALVE STRUCTURE.

1,361,570.

Specification of Letters Patent.

Patented Dec. 7, 1920.

Application filed August 23, 1919. Serial No. 319,436.

To all whom it may concern:

Be it known that I, LUCIEN T. EARNHEART, a citizen of the United States, and a resident of Saunemin, county of Livingston, and 5 State of Illinois, have invented a certain new and useful Air-Valve Structure; and I do hereby declare that the following is a full, clear, and exact description thereof, reference being had to the accompanying drawings, in which like numerals refer to like parts.

The invention herein set forth, relating to a pressure indicating air valve, is an improved construction over that shown in Letters Patent to Chauncey B. Earnheart No. 1,305,265 and No. 1,305,266.

One feature of the invention herein consists in providing a lower valve for positively closing the outlet from the tire, after 20 it has been inflated, making the construction such that said valve will be closed by the operation of the collar or other means for screwing down and tightening the gage member, said valve being mounted on a long 25 stem guided by the means below the valve and loosely mounted adjacent to the lower end of the gage member so that the valve will move by the movement of the gage member.

30 Another feature of the invention consists in combining with the foregoing a rubber tube connecting the lower inner end of the gage member with the inner end of the valve structure and surrounding the stem by a wire spring connected at one end of the gage member and to the other end of the lower 35 part of the valve structure for yieldingly resisting the outer movement of the gage member and providing spiral grooves in the 40 casing for guiding the reciprocating movement of the gage member and valve for the torsional movement of the wire spring.

The full nature of this invention will be understood from the following description 45 and claims.

In the drawings Figure 1 is a central vertical section through the entire valve structure omitting the cap. Fig. 2 is a similar view partly in section and partly in elevation, showing the gage member moved outwardly as compared to its position in Fig. 1. Fig. 3 is a section on the line 3-3 of Fig. 1. Fig. 4 is a section on the line 4-4 of Fig. 1. Fig. 5 is a vertical section of a portion of the

valve casing. Fig. 6 is a section on the line 55 6-6 of Fig. 2.

There is shown in the drawings a short valve stem 10 with a simple free air passage 11 therethrough and with a flange 12 on the lower end, whereby it is secured to the pneumatic tire, which is not shown. There is an outer casing 13 which is internally threaded at its lower end where it screws on the valve stem 10. This casing is externally threaded, not shown, like the usual valve stems of other 60 constructions for receiving the usual dust cap also not shown. The outer end of the casing 13 is externally reduced in diameter and threaded at 14 to receive the collar 15 which screws or slips thereon for the purpose 65 70 hereinafter explained.

The outer end of the short valve stem 10 is reduced somewhat in diameter, but not externally threaded. Over the reduced end of the stem 10 the spring holder 17 fits, the 75 external surface of which is hexagonal and smooth, as seen in Fig. 3. The corners 17^A made by the hexagonal faces of the holder 17 enter complementary V-shaped ways formed in the casing, as shown in Fig. 3. 80 The spring holder 17 has a reduced upper portion to form an outer shoulder 18 which abuts against the overhanging portions of the casing 13 at the upper ends of the V-shaped ways. The spiral spring 19 surrounds 85 the reduced portion of the spring holder 17 and abuts against the shoulder 18. Within the spiral spring there is a flexible air tight tube 20, the lower end of which projects into the spring holder 17 surrounding 90 the conical and large portion 21 of the tubular metal union 22, which forms a connection between said flexible tube and the valve stem 10. The lower end of the union 95 projects into a suitable seat formed in the upper part of the valve stem. The lower end of the flexible tube extends downwardly beyond the conical enlargement 21 and forms a gasket or washer by extending inwardly beneath the reduced lower end of the union 22 and above the reduced upper portion of the stem 10 between which it is clamped. The spring holder 17 has a complementarily 100 formed conical tubular enlargement in its inner surface to receive the conical enlargement 21 of the union 22 and the flexible tube 20. Therefore, when the casing 13 is screwed 105 down on the valve stem 10, it forces the

conical inner wall of the spring holder 17 down on the flexible tube 22 and makes an air tight joint.

Around the upper end of the rubber tube 20 there is another spring holder 25 which is vertically movable in the casing 13. It has a lower reduced portion to which the upper end of the spring 19 is secured. The upper end of the spring holder 25 is internally threaded to receive the lower externally threaded end 26 of the tubular gage member 27. There is an upper metal tubular union 22 similar to the union 22 at the lower end of the structure for securing the upper end of the flexible tube 20 in place with an air tight connection as described. The gage member 27 is subject to the direct pressure of the air in the pneumatic tire while being charged, and such air pressure is indicated by graduations and numerals on said gage member 27, as seen in Fig. 2, as they appear above the upper end of the casing 13, when the collar 15 is released from casing 13. The member 27 also carries a check valve 28 which is of the usual type.

The gage member 27 is threaded at its upper end to receive the nipple of the hose for inflation. There is an annular groove 30 in said member 27 being reduced in diameter, just above the graduations to receive the inturned flange 31 of the collar 15. Below said flange 31 there is an internal threaded portion 32 which is adapted to screw on the upper threaded end of the member 27. When the collar 15 is being put in place, the flange 31 does not extend inwardly, as shown, but is concentric with the threaded upper end of the gage member, and projects in alignment with the body of the collar, so that the collar can be screwed or slipped on and over the threaded portions of the member 27 down to its position shown in Figs. 1 and 2. The flange 31 is then bent inward by mechanical means so as to project into the groove 30 and hug the reduced portion of the member 27 and prevent the escape or removal of the collar 15 therefrom. Said collar, therefore, is fixed in its location on the member 27 so it can move neither up nor down, but can turn thereon. When it is desired to inflate the tire or ascertain the air pressure in the tire, the collar 15 is unscrewed from the upper end of the casing 13, as seen in Fig. 2. After the tire is inflated, it is screwed down in place, as shown in Fig. 1.

The lower end of the gage member 27 has an enlarged recess 34 at the lower end of the passageway 35 therethrough and into which the upper reduced portion of the upper union 22 projects. In this chamber 34 a skeleton head 36 loosely fits and said head is secured on the valve stem 37 that carries the shut-off lower valve 38 and extends down through the lower union 22 for some

distance, so that said lower union guides the valve stem 37 in its vertical movement. The valve 38 seats on the upper end of the lower union 22, and is so placed on this valve stem that when the collar 15 is screwed down, as shown in Fig. 1, after the tire has been inflated, the downward movement of the gage member 27 will force the valve stem 37 down and close the valve 38, as shown in Fig. 1. This will hermetically seal the valve structure positively and prevent the escape of air from the tire. When it is desired to inflate the tire, the collar 15 is unscrewed to the position shown in Fig. 2, which lifts the gage member 27 and carries with it the valve stem 37 which opens the lower valve 38.

The spring 19 has a tendency toward a torsional movement when it is expanded by the air pressure as seen in Fig. 2 and to accommodate the valve structure to that occasion or condition, the valve casing 13 has a pair of oppositely located longitudinal grooves 40 in the inner surface thereof arranged in a slightly oblique or spiral form, as shown in Fig. 5 and into these grooves 40 fins 41 from the gage member 27 project and prevent said member from undue turning in the casing 13. The spiral grooves 40 extend to the base but do not extend entirely through the upper end of the casing 13 so that the gage member cannot be removed from the casing outwardly.

The opening through the upper union 22, it is observed, is made large enough to permit the insertion or removal through it of the valve 38 in assembling the device. The skeleton head 34 does not obstruct the free passage of air from or to the passage 35 in the gage member 27.

The invention claimed is:

1. In a valve structure having a valve seat near the inner end of the structure, a valve engaging said seat and closing the air passageway through the structure, a reciprocable gage member with an air passageway therethrough and with the inner end provided with an enlarged chamber, a skeleton connection upon said valve and secured in said gage member chamber, whereby the valve will be opened and closed by the gage member and permit the free flow of air therethrough, and an elastic air tight connection between the inner end of the gage member and surrounding the passageway therein and the enlarged chamber and the lower part of the valve structure for forming a part of the air passageway to insure the free axial flow of air through the communicating passageways of said air valve structure.

2. In a valve structure having a valve seat near the lower and inner end of the valve structure, a valve engaging said seat and closing the air passageway through the structure, a valve stem on which said valve

- is secured which extends upwardly through the air passageway, a reciprocable gage member adapted to be forced outward by the back air pressure to indicate the degree of 45 such air pressure and having an air passageway therethrough with the inner end provided with an enlarged chamber, elastic tubular means connecting said gage member and said valve structure, said tubular means 50 being arranged so that there will be a free air passageway through said elastic connection in alinement with the air passageways through the gage member and the lower part of the valve structure, and a skeleton 55 connection upon said valve stem seatably secured in the enlarged chamber and inner end of the gage member which enables the latter to operate the valve and permits the free flow of air through the communicating 60 20 passageways of the air valve structure.
3. An air valve structure including a casting having spirally disposed longitudinal grooves therein, a gage member slideable therein having fins projecting into said 65 grooves, and a spiral spring secured to the inner end of the gage member and to the inner part of the structure tending to resist the outward movement of the gage member, whereby said grooves will cause the gage 70 30 member in its movement to allow for the torsional movement of the spring.
4. An air valve structure including a casting, a valve for closing the passageway through the inner end of the valve structure, a valve stem on which the valve is 75 35 mounted, a gage member slideable in said casting having an air passage therethrough and with the inner end provided with an enlarged chamber, a flexible tube connecting the inner end of said gage member to the inner end of the valve structure, a tubular union for securing the outer end of the tube to the gage member, and a skeleton head on the upper end of said valve stem which lies 80 40 85
- in said chamber and which is of greater diameter than the opening in said union, whereby the movement of the gage member will cause a corresponding movement of the valve.
5. In a valve structure having a valve seat near the inner end of the structure, a valve engaging said seat and closing the air passageway through said structure, a reciprocable gage member with an air passageway therethrough, means connecting said valve and said gage member whereby the latter may open and close said valve, elastic means for connecting the inner end of said gage member with the lower part of the valve structure for substituting for and 60 forming a part of said air passageway, and radially projecting fins on said gage member adapted to engage correspondingly-shaped torsion grooves in said valve structure for preventing said gage member from turning 65 therein other than the movement allowed for torsion when said member is reciprocated.
6. A valve structure having a valve seat near the inner end of the structure, said structure having a longitudinally extending 70 groove terminating near the top thereof, a valve engaging said seat and closing the air passage through the structure, a reciprocable gage member with an air passageway therethrough, an elastic connection forming a 75 part of said air passageway between the inner end of the gage member and the lower part of the valve structure, and a projection on said gage member adapted to extend into said groove for preventing said gage member 80 from turning therein a greater amount than necessary to compensate for the torsional movement of said elastic connection means and for preventing said gage member from leaving the structure. 85

In witness whereof, I have hereunto affixed my signature.

LUCIEN T. EARNHEART.
